UNITED STATES PATENT OFFICE.

JEREMIAH A. SCRIVEN, OF NEW YORK, N. Y.

DESIGN FOR A BIFURCATED NETHER GARMENT.

SPECIFICATION forming part of Design No. 35,399, dated December 3, 1901.

Application filed April 4, 1901. Serial No. 54,393. Term of patent 14 years.

To all whom it may concern:

Be it known that I, JEREMIAH A. SCRIVEN, a citizen of the United States, residing in the borough of Manhattan, city, county, and State 5 of New York, have invented a certain new and useful Design for a Bifurcated Nether Garment, of which the following is a specification.

The leading feature of my design is a bifurcated nether garment with elastic insertion-strips crossing at or about the crotch and extending from about the lower front end of 10 the tubular members to about the front upper edge of the body of the garment.

In the accompanying drawings I have shown 15 a garment embodying my design.

In this drawing, 1 represents the body portion of the garment, 2 2 represent tubular members thereof, and 3 and 4 indicate elastic insertion-bands set diagonally of the garment and intersecting at the point 5. ²⁰

Having described my design, what I claim is—

The design for a bifurcated nether garment, substantially as herein shown and described.

JEREMIAH A. SCRIVEN.
